Universal Slide Fastener Co. Inc., Long Island
City, N. Y., a corporation of New York

Application November 1, 1940, Serial No. 363,805

17 Claims. (Cl. 29—34)

This invention relates to a method and means for rapidly forming long strips of integrally connected slide fastener elements by progressively coining groups of fastener elements in flat stock in a high speed reciprocating power press and for accurately spacing the individual elements and groups of elements along the strip by means of anchoring and piloting mechanisms.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the claims.

In the accompanying drawings, in which is shown one of the various possible embodiments of this invention:

Fig. 1 is a front view of a press embodying my invention;

Figs. 2, 3 and 4 are enlarged sectional views taken along the lines 2—2, 3—3, 4—4 of Fig. 1, and illustrating respectively the stationary die, the moving die and the stripping plate;

Fig. 5 is a sectional view through the dies when the same are in operative relationship, the same being taken along the line 5—5 of Fig. 2;

Figs. 6, 7 and 8 are sectional views taken along the lines 6—6, 7—7, 8—8 of Fig. 5, and illustrating respectively the action of the stripping finger, the anchoring die and the piloting die;

Fig. 9 is a perspective view in partial section showing the die members of the press in the process of forming a strip containing a series of slide fastener elements;

Fig. 10 is a perspective view of the stationary die;

Fig. 11 is an enlarged perspective view of an individual slide fastener element separated from the formed strip;

Figs. 12, 13 and 14 are top, side and bottom views, respectively, of a strip formed in accordance with my invention; and

Fig. 15 is a sectional view of said strip taken along the line 15—15 of Fig. 13.

Generally, I accomplish the foregoing objects by stamping a strip of continuous stock with a pair of cooperating dies to form a series of slide fastener elements, the shaped head of each of which is nested between and integral with the spread legs of the next following element. In this manner no stock whatsoever is interposed between adjacent elements in the strip and waste of material and space occupied by the ele-

ments are thus reduced to a minimum. The strip is formed with great speed and accuracy by stamping successive groups of heads and serrating the edges of the strip to provide the outer edges of the jaws. In order to insure the proper spacing between groups of elements thus stamped, I also provide anchoring and piloting mechanisms in association with the head forming and serrating dies. The formed strip, after stamping, is wound about a suitable holding device, such as a bobbin, and is subsequently fed into an assembling machine where single elements are successively severed from the end of the strip and clamped immediately prior to complete severance in spaced relationship onto the beaded edge of a stringer tape.

Referring now to Figs. 1 through 10, I have illustrated a high speed reciprocating power press 40 which employs cooperating die members constructed in accordance with my invention to work a narrow, thin, flat continuous strip of stock. Said press comprises a frame 42 on which are supported a pair of vertical standards 43 and a horizontal bed plate 44. Constraining slides 45 are provided in the standards 43 to receive a cross-head 46 on the lower face of which is adjustably mounted an upper die shoe 48. The crosshead 46 is driven by a connecting rod 50 journaled at its other end about a crank shaft 52 which is supported in bearings 54 attached to the upper end of the standards 43, and which is driven by a belt 56 and pulley 58 from a suitable source of power. A strip feeding means 60, such as is well known in the art, is mounted on the bedplate 44 and is actuated by the crank shaft 52 through the linkage system illustrated at 64. The strip feeding means 60 is adjusted and synchronized to feed at one stroke, while the dies are separated, a predetermined length of strip S which in the illustrated embodiment of my invention is substantially equal to the span of four heads (see Fig. 12).

The upper die 66 (Figs. 3, 5, and 9), which is carried in a jacket 67 fixedly mounted in the shoe 48, comprises a die block 68 received in a recess 69 in the jacket 67 and held by a screw 70 against a hardened backing plate 71 which is caught between the shoe 48 and jacket 67. Said die block 68 is provided with a plurality of identical aligned recesses 72 and is so shaped as to impart to the upper surface of the strip S the configuration indicated in Figs. 12, 13 and 15.

In the form illustrated, the die block 68 contains ten recesses 72 and is therefore adapted to simultaneously stamp a group of ten heads al-

though a length of strip S equivalent only to four heads is advanced between each stroke of the crosshead 46. Due to this construction, the first four recesses 72a and the portions of the die 68 associated therewith will on each downward stroke coin the upper surface of a blank portion of the strip S while the second six recesses 72b and associated portions of the die 68 will simultaneously fit over a stamped group of six heads and anchor or re-strike that portion of the strip, thus ensuring accurate spacing between successive groups which spacing would otherwise be varied due to the flowing of metal in the strip during the coining operation.

Although I have found that a ratio between the lengths of the coining portion 72a and the anchoring portion 72b in the order of four to six has given highly satisfactory results, I also contemplate the use of longer or shorter anchoring portions immediately following the coining portion.

It will be noted that the strip S is appreciably broadened during swaging so that the flat stock may originally be furnished somewhat narrower in size than the over-all width of the formed strip shown in Fig. 12.

Adjacent the recess 69 in the jacket 67 I provide an aligned slightly larger recess 73 for holding the dies which cut out serrations along the sides of the strip to form the edges of the jaws. These dies comprise a pair of parallel two-section shearing punches 74 and 75, each of which has a pair of spaced serrated cutting edges 76 and 78. The serrated edges 78 have their lower faces 78a disposed a short distance below the lower faces 76a of the serrated edges 76. The punches 74 and 75 may be force-fitted in the recess 73 and maintained in proper relationship relative to each other and the die block 68 by means of a spacing block 79 and a guiding heel 80. In order to facilitate assembly of the punches 74 and 75 in the recess 73, the corners thereof may be relieved as indicated at 81.

The serrated cutting edges 76 and 78 are so designed in this form of my invention that they will cut a group of serrations comprising the outer edges of four jaws in predetermined relationship to a corresponding group of four heads previously formed in the coining operation. However, only the first groups of edges 76 actually perform any cutting. The second groups 78, due to the position of their lower faces 78a, engage the strip S in serrations previously cut by the edges 76 before the next group of serration is cut and thus pilot said strip. In this manner I ensure proper registration relative to the strip of the coining and anchoring portions 72a and 72b as well as the cutting edges 76. The piloting edges 78 should be slightly raked, as indicated at 78b, to facilitate bringing the strip into registration.

Although I have shown the piloting edges 78 as consisting of a plurality of serrations equal to the number of heads and jaw edges coined and cut in one group, and as being spaced from the cutting edges 76 a distance approximately equal to the span of these cutting edges, it will be understood that more or fewer piloting serrations may be employed and that these serrations may be spaced closer to or further away from the cutting edges 76. It will be noted, however, that the space between the nearest disposed piloting and cutting serrations is equal to a whole multiple of the span of adjacent cutting serrations.

A lower stationary die-shoe 82 (Figs. 2, 5, 9, 10)

is bolted down to the bedplate 44 and carries a jacket 83 having an elongated recess 84 cut therethrough and provided with channels 85 to receive the guiding heels 80 in a sliding fit. Suitably mounted in one end of the recess 84, as by a screw and backing plate 83a similar to the screw 70 and backing plate 71, is a lower die block 86 from which projects a group of ten identical aligned nubs 87, each of said nubs being in registration with a corresponding recess 72 in the upper die block 68. The nubs 87 are so shaped as to impart to the lower surface of the strip S the configuration indicated in Figs. 13, 14 and 15. Also, as in the case of the upper die portions 72a and 72b, the first four nubs 87a perform a coining operation while the last six nubs 87b are employed for anchoring.

It will be appreciated from the foregoing description that the coining recesses 72a and the coining nubs 87a are respectively identical in configuration and spacing to the anchoring recesses 72b and anchoring nubs 87b so that during anchoring although the previously shaped heads are restruck they are not reformed. However, as noted above, the ratio between the number of coining die elements and anchoring die elements is not a critical feature of my invention. To denote the similarity between the coining and anchoring die elements the same will be referred to in the claims as like elements, the term "like" therefore denoting identity in configuration of the die elements but not necessarily identity of number.

Similarly mounted at the other end of the recess 84 is a holding block 88. Channels 89 and 90, cut in facing sides of the blocks 86 and 88, receive in a force fit the opposite ends of an anvil 91. Said anvil is provided with groups of serrations 92 and 93 which cooperate with the cutting edges 76 and 78, respectively, to shape the longitudinal edges of the strip S. The anvil also divides the space between the channels 85 into a pair of passageways 94 aligned with passageways (not shown) in the mounting plate 83a and bedplate 44 through which scrap 95 struck from the edge of the strip S may fall.

I have also provided a pair of shoulders 92a and 92b at both ends of the serrated portions 92 between which pieces of scrap 95 struck from the strip S are squeezed and temporarily held to prevent them from sticking to the punches 74 and 75.

It will be seen that due to the construction above described, the several dies are rigidly and accurately held in assembled position and may be easily and readily disassembled for replacement, so that a high standard of precision can be maintained.

In order to prevent the strip S from sticking to the dies, upper and lower strippers are provided. The lower stripper (Figs. 5 and 10) comprises a plunger 96 which slides in a bore 97 formed in the bedplate 44 and is urged upwardly by means of a compression spring 98. Extending vertically upward from the plunger through a bore in the jacket 83 is a stripper finger 99 having a rounded upper end which resiliently presses against the bottom face of the unformed portion of the strip S so as to press the same upwardly and away from the nubs 87 on the lower die 86. Upward movement of the finger 99 is limited by abutment of the plunger 96 with the backing plate 83a.

A stripper 100 (Figs. 4, 5, 9) prevents the strip S from following the upper die 68 during rising movement of the crosshead 46. Said stripper 100 may comprise a pair of flat side pieces 102 and

104 screwed to the stationary die jacket 83 and provided with a pair of flanges 105 spaced from the upper face of the jacket. Pinned to the lower surface of said flanges 105 are three abutting stripper plates 106, 107 and 108 having a plurality of apertures 110, 112 and 114 formed therein to allow the upper die block 68 and punches 74 and 75 respectively to freely pass through the stripper 100. The under surface of the stripper plates 106 and 108 are provided with a channel 116 to guide the strip S through the press 40 between the feed and take-up bobbins B.

Posts 118 and 120, fixed to the lower die shoe 82 and passing through guide bushings 122 in the upper die shoe 48, ensure proper alignment of 18 the coining and shearing dies.

Particular attention is directed to the arrangement and shape of the slide fastener elements in the strip S. Said elements are all faced in the same direction in the strip S (see Figs. 12-14) and each element comprises a head 130 having the usual locking projection 132 and underlying socket 134. The projection 132 is provided with front, side and rear sloped guiding surfaces 136, 138 and 140 joined by concavely rounded corners 142 and abrupt edges 143. Said projections 132 rise from between a pair of parallel co-planar flats 144 and 146, which are joined by slopes 148 to the upper surface 150 of the jaws 152.

It will be noted that the lowest point 154 on the rear guiding surface 140 is disposed below the jaw surface 150, thus enabling the elements to clear each other more easily in the interlocking operation.

The jaws 152 comprise a pair of spread legs 155, which are cut from the flats 144 and 146 along the dotted lines indicated in Fig. 21, in a manner hereinafter to be described. Each of the legs 155 projects angularly from its associated head 130 and includes an inner portion 156 (Fig. 12) which lies outside of and immediately adjacent the locking projection 132 on the next following slider element; an intermediate portion 158 which lies outside of and immediately adjacent a flat portion 160 of the locking projection on the next following slider element; and an outer portion 162 which comprises one of the serrations forming an edge of the strip S.

By forming and arranging the various parts of the slide fastener elements in this fashion, with the head of one element integral with and nested between the spread legs of the next following element, I have eliminated all waste incident to the fabrication of slide fastener strings, except the scrap 95 struck from the sides of the strip S, and also the elements thereby occupy the minimum length possible.

It will thus be seen that there is provided an apparatus and method for making strips of integrally connected slide fastener elements in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:

1. An apparatus for manufacturing from blank stock a continuous strip having a series of spaced slide fastener interlockable projections and under-

lying sockets uniformly formed and regularly positioned thereon, said apparatus comprising means to stamp a group of identical interlockable projections and underlying sockets in said blank stock, means to subsequently notch identical shaped portions out of the longitudinal edges of said stock at regular intervals in such relationship to the already stamped projections and sockets as to provide square corners on the jaws of slide fastener elements which may be severed from the strip and attached to a tape, and piloting means adapted to cooperate with the notched longitudinal edges to ensure accurate positioning of the stock in relation to the stamping and notching means.

2. An apparatus for manufacturing from blank stock a continuous strip having a series of spaced slide fastener interlockable projections and underlying sockets uniformly formed and regularly positioned thereon, said apparatus comprising means to stamp a group of identical interlockable projections and underlying sockets in said blank stock, means to subsequently punch a group of serrations in the longitudinal edges of said stock at regular intervals in such relationship to the already stamped projections and sockets as to provide square corners on the jaws of slide fastener elements which may be severed from the strip and attached to a tape, piloting means adapted to cooperate with said serrations for maintaining said stock in proper registration with said stamping and punching means, and a common support for said punching means and said piloting means, said piloting means being disposed so as to lead said punching means.

3. An apparatus for manufacturing from blank stock a continuous strip having a series of spaced slide fastener interlockable projections and underlying sockets uniformly formed and regularly positioned thereon, said apparatus comprising means to stamp a group of identical interlockable projections and underlying sockets in said blank stock, a punching die having a plurality of teeth adapted to form a group of serrations in the longitudinal edges of said strip in such relationship to the already stamped projections and sockets as to provide square corners on the jaws of slide fastener elements which may be severed from the strip and attached to a tape, the teeth in said die being identically shaped and identically disposed with respect to each other, and a piloting die having at least one tooth of the identical shape of the teeth in said punching die, said piloting tooth being spaced with respect to the endmost tooth in the punching die a distance equal to a multiple of the span between adjacent teeth thereon.

4. An apparatus for manufacturing from blank stock a continuous strip having a series of spaced slide fastener interlockable projections and underlying sockets uniformly formed and regularly positioned thereon, said apparatus comprising means to stamp a group of identical interlockable projections and underlying sockets in said blank stock, a punching die for serrating the longitudinal edges of said strip at regular intervals in such relationship to the already stamped projections and sockets as to provide square corners on the jaws of slide fastener elements which may be severed from the strip and attached to a tape, and a piloting die having portions thereof identical with portions of said punching die and adapted to cooperate with the serrations formed by said punching die, the lower

end of said piloting die being raked and disposed below the end of said punching die.

5. In a method of manufacturing from a blank strip of stock a continuous strip having a series of spaced slide fastener interlockable projections and underlying sockets uniformly formed and regularly positioned thereon, the steps comprising successively stamping adjacently disposed groups of identical interlockable projections and underlying sockets along the length of said strip, serrating the longitudinal edges of said strip in such relationship to the already stamped projections and sockets as to provide square corners on the jaws of slide fastener elements which may be severed from the strip and attached to a tape, advancing the strip between successive group stamping operations, and employing the endmost projection and socket of an immediately previously formed group to anchor the strip during the next succeeding group stamping operation.

6. In a method of manufacturing from a blank strip of stock a continuous strip having a series of spaced slide fastener interlockable projections and underlying sockets uniformly formed and regularly positioned thereon, the steps comprising successively stamping adjacently disposed groups of identical interlockable projections and underlying sockets along the length of said strip, serrating the longitudinal edges of said strip in such relationship to the already stamped projections and sockets as to provide square corners on the jaws of slide fastener elements which may be severed from the strip and attached to a tape, advancing the strip between successive group stamping operations, and employing the immediately previously formed group of projections and sockets to anchor the strip during the next succeeding group stamping operation.

7. In a method of manufacturing from a blank strip of stock a continuous strip having a series of spaced slide fastener interlockable projections and underlying sockets uniformly formed and regularly positioned thereon, the steps comprising successively stamping adjacently disposed groups of identical interlockable projections and underlying sockets along the length of said strip, regularly serrating the longitudinal edges of said strip in such relationship to the already stamped projections and sockets as to provide square corners on the jaws of slide fastener elements which may be severed from the strip and attached to a tape, advancing the strip between successive group stamping operations, and employing a previously formed serration to pilot the strip during a succeeding stamping and serrating operation.

8. In a method of manufacturing from a blank strip of stock a continuous strip having a series of spaced slide fastener interlockable projections and underlying sockets uniformly formed and regularly positioned thereon, the steps comprising successively stamping adjacently disposed groups of identical interlockable projections and underlying sockets along the length of said strip, punching out regular groups of identical portions from the longitudinal edges of the strip in such relationship to the already stamped projections and sockets as to provide square corners on the jaws of slide fastener elements which may be severed from the strip and attached to a tape, advancing the strip between successive group stamping operations, and employing the punched out portions to pilot the strip for succeeding group stamping and punching operations.

9. An apparatus for manufacturing from blank stock a continuous strip having a series of spaced

slide fastener heads uniformly formed and regularly positioned thereon, each head including an interlockable projection and an associated underlying socket, said apparatus comprising means to simultaneously stamp in said blank stock at successive intervals a group of identical heads by intermittently cold flowing the metal in a portion of the stock under pressure between a pair of dies whose working faces negatively match the upper and lower surfaces of a plurality of successive, uniformly spaced and identically oriented heads, anchoring means to maintain constant the spacing between adjacent heads, said anchoring means including a pair of like dies immediately adjacent said first mentioned pair of dies for reconfining a plurality of previously stamped heads including the rearmost one thereof, during the stamping of the next following group of heads the foremost of which is immediately adjacent such already stamped rearmost head, so as to restrike without reforming a plurality of previously stamped heads including such already stamped rearmost head while the next following group of heads is being stamped, means to intermittently feed said strip to and beyond said stamping and anchoring means a distance equal to the number of heads stamped by the stamping means.

10 10. An apparatus as set forth in claim 9 wherein the dies comprising the stamping means are so shaped as to stamp at both sides of each head material along the longitudinal edges of the strip from which material jaws associated with the heads may be formed and wherein the dies comprising the anchoring means are so shaped as to restrike without reforming said material to both sides of each head as each head is restruck, said stamping and anchoring dies being so shaped that the heads and the jaws associated therewith are contiguous in the strip, whereby no scrap or waste material is present between adjacent heads and the material from which adjacent jaws are formed.

11 11. An apparatus for manufacturing from blank stock a continuous strip having a series of spaced slide fastener heads uniformly formed and regularly positioned thereon, each head including an interlockable projection and an associated underlying socket, said apparatus comprising a row of several serially, identically arranged and spaced, identical die stamping elements for forming a linear group of identical heads by intermittently cold flowing the metal in a portion of the stock under pressure between said die stamping elements, and means for feeding said stock intermittently along said row a distance equal to the span of a whole number of said elements, which number is a plurality less than the number of all of said elements, so that less than all of said elements will form heads in said blank stock at each stamping stroke and the remaining plurality of elements will act as anchoring members which maintain a constant spacing between adjacent heads in successively stamped groups of heads.

12 12. An apparatus for manufacturing from blank stock a continuous strip comprising a series of directly joined slide fastener elements, each slide fastener element including an interlockable projection and an associated underlying socket, said projections and sockets being uniformly formed and regularly positioned and spaced along the strip, said apparatus comprising a single upper die and a single lower die, said upper die having a working face which negatively matches the

upper surface of a portion of said strip including a plurality of successive fastener elements, said lower die having a working face which negatively matches the lower surface of said portion of the strip, the upper and lower dies providing a series of fastener element forming impressions, said impressions being identical, and each being of a shape corresponding to a finished fastener element, said impressions merging one into the other, means to move said dies toward and away from each other, and means to intermittently feed said strip to and beyond said dies a distance equal to the span of a whole number of fastener elements less than all the fastener elements in said portion.

13. In a method of manufacturing from blank stock a continuous strip having a series of spaced slide fastener heads uniformly formed and regularly positioned thereon, each head including an interlockable projection and underlying socket, the steps comprising stamping a head in said blank stock at successive intervals by intermittently cold flowing the metal in a portion of the stock under pressure between a pair of dies whose working faces negatively match the upper and lower surfaces of a head, and maintaining constant the spacing between adjacent heads by restriking without reforming a plurality of previously stamped heads including the rearmost one thereof during the stamping of the next following head which is immediately adjacent such already stamped rearmost head, said restriking being effected by reconfining between like dies said plurality of previously stamped heads while the next following head is being stamped.

14. A method as set forth in claim 13 wherein the strip is fed intermittently a distance equal to the number of heads stamped.

15. In a method of manufacturing from blank stock a continuous strip having a series of spaced slide fastener heads uniformly formed and regularly positioned thereon, each head including an interlockable projection and underlying socket, the steps comprising simultaneously stamping in said blank stock at successive intervals a group of identical heads by intermittently cold flowing the metal in a portion of the stock under pressure between a pair of dies whose working faces negatively match the upper and lower surfaces of a plurality of successive, uniformly spaced and identically oriented heads, and maintaining the same relative position between adjacent heads

5 in successive groups as between adjacent heads in the groups by restriking without reforming a plurality of previously stamped heads including the rearmost one thereof during the stamping of the next following group of heads the foremost of which is immediately adjacent such already stamped rearmost head, said restriking being effected by reconfining between like dies said plurality of previously stamped heads while said 10 next following group of heads is being stamped.

16. A method as set forth in claim 15 wherein during stamping the stock is so shaped as to provide material at both sides of the heads from which jaws associated with each head can be 15 formed, wherein during restriking said material from which jaws can be formed is restruck without reforming each time a head is restruck, and wherein the heads and material from which the jaws are formed are stamped in contiguous relationship 20 so that no scrap or waste material is present between adjacent heads and the material from which adjacent jaws are formed.

17. An apparatus for manufacturing from blank stock a continuous strip having a series of spaced slide fastener heads uniformly formed and regularly positioned thereon, each head including an interlockable projection and an associated underlying socket, said apparatus comprising means to stamp at least one head in said blank 25 stock at successive intervals by intermittently cold flowing the metal in a portion of the stock under pressure between a pair of dies whose working faces negatively match the upper and lower surfaces of the number of heads stamped, anchoring 30 means to maintain constant the spacing between adjacent heads, said anchoring means including a pair of like dies immediately adjacent said first pair of dies for reconfining a plurality of previously stamped heads, including 35 the rearmost one thereof, during the stamping of the next following head which is immediately adjacent said already stamped rearmost head, so as to restrike without reforming a plurality of previously stamped heads including such already stamped rearmost head while the next following head is being stamped, and means to 40 intermittently feed said strip to and beyond said stamping and anchoring means a distance equal to the number of heads stamped by the stamping 45 means.

50 MAURICE VOITY.
